NEEDLE FOR USE IN THE PRODUCTION OF
KNITTED FABRICS

Robert Kirkland Mills, Sherwood, Nottingham, England, assignor to Hosiery Developments Limited, Nottingham, England

Application February 4, 1933, Serial No. 655,236
In Great Britain February 5, 1932

4 Claims. (Cl. 66—121)

This invention comprises improvements in needles for use in the production of knitted fabrics and refers more particularly to needles of the pivoted latch type.

With latch needles as at present constructed the disadvantage exists that during the retraction of the needle in stitch production to knock-over there is a decided tendency for the closing latch to nip and have a shearing or scissoring action upon the loop of thread carried on the needle between the latch pivot and the needle hook, such shearing or scissoring action being caused by the progressively and rapidly decreasing angle between the closing latch and the needle shank coupled with the simultaneous receding of the vertex of such angle from the latch pivot towards the hook.

An important object of the present invention is to provide a knitting needle wherein the aforesaid shearing or scissoring action is eliminated; and with this object the needle in accordance with the present invention is so constructed that during the closing movement of the latch on to the needle hook no part of said latch has any scissoring or shearing action with any part of the needle shank. This is advantageously accomplished by so constructing the needle that during the final half of the closing movement of the latch on to the hook, the vertex of the angle between said latch and the needle shank, i. e. the base of the thread-receiving space between the latch and shank, is maintained at a uniform or approximately uniform distance from the axis of the latch pivot.

The pivoted latch of the improved needle is so shaped at the part thereof adjacent to the pivot that the thread-accommodating space between a fully closed latch and the opposing face of the needle shank extends down to a position substantially near to or level with the latch pivot.

Although the improved needle can be employed with considerable advantage for producing all kinds of knitted fabric, it is especially applicable for use in the production of knitted fabric embodying locked or tied stitches which prevent or resist laddering or roving in the fabric, and in particular to the production of that type of fabric described in the specification of my prior Patent No. 1,960,161 wherein the locked or tied stitches are produced by passing a thread loop formed on the needle through and also closely around another loop on said needle so as to tie one loop upon another.

In the production of ladderproof or ladder-

resisting fabric as above, during the retracting movement of the needle for knocking over, the thread loop which is to be retained on the needle is pulled down into the base or vertex of the angular space between the closing latch and the needle shank near the latch pivot, consequently it will be appreciated that if any shearing or scissoring action takes place between the latch and the shank during the closing movement of the latch there is a real danger of the set thread loop being nipped and/or sheared. This danger is, however, obviated by constructing the needle in accordance with the present invention. Additionally, during the final part of the retracting movement of the needle for knocking-over the retained thread loop traverses the inner face of the closed latch, and in order positively to prevent said retained thread loop from inadvertently passing off the needle between the point of the needle and the tip or spoon of the latch, said hook point is in the present invention completely and snugly buried within a spoon or cup-shaped portion at the latch tip in such a manner that the thread cannot come into engagement with said buried hook point, and is consequently passed into and retained within the hook.

For the purpose of more fully describing the nature of this invention, reference will now be made to the accompanying drawing, wherein:

Figure 1 illustrates a single latch needle constructed in accordance with the present invention, the latch being shown in dotted lines in the half open and fully open positions. Figure 2 illustrates a double latch needle applicable for producing non-ladder or ladder-resisting fabric.

In one convenient method of carrying out the present invention the knitting needle is provided in the usual manner with a hook 1 and a latch 2 pivoted to the needle shank 3 a short distance from the hook. That part of the shank to which a latch is pivoted is preferably formed with a swell or curved bulge 4. The pivoted or jointed part of the latch 2 may have a circular or approximately circular part 5 encircling the pivot 6, said part 5 constituting an enlarged termination of a cranked portion 7 of the latch which is curved or shaped so as to extend at approximately right angles to the main part of the latch. By this means, when the latch is in the fully closed position, i. e. in engagement with the hook 1, the thread-accommodating space between the inner face of the latch and the opposing face of the shank above the pivot 6 extends down to a position substantially near to or level with said pivot,

and the vertex 8 of the angle of said space is somewhat rounded as distinguished from a sharp or acute angle.

A very important characteristic of the needle 5 in accordance with this invention is that during the final half of the closing movement of the latch, in which closing movement the latch swings through an arc approximating 180°, i. e. from a position wherein the latch extends at approxi- 10 mately right angles to the shank as indicated in dotted lines to a position engaging the hook, no part of the latch has a scissoring action with the shank; consequently, during the retracting movement of the needle to knock-over, the possibility 15 of thread located in the vertex 8 of the aforesaid angular space being sheared or nipped is effectively obviated. Additionally, the relative formation of the latch adjacent to its pivot and of the inner curved face of the shank portion 4 near 20 said pivot is such that during the aforesaid final half of the closing movement of the latch the distance between the axis of the pivot 6 and the vertex 8 of the thread-accommodating space is maintained constant or approximately so, instead of 25 becoming gradually greater as is the case with all latch needles previously employed or proposed. The shape of the latch at its cranked part 7 is advantageously such as to provide a substantially J-shaped recess on its inner side between the main 30 part 2 and the enlarged circular part 5; and in so shaping the latch it is found advantageous to form the part 5 of involute shape, i. e. eccentric to the pivot 6.

As before-stated, the improved latch needle is 35 particularly suitable for use in knitting non-ladder or ladder-resisting fabric of the type before-mentioned wherein locked or tied stitches are produced by passing a thread loop through and also closely around another loop on the needle so as to tie one loop upon another. In knitting this 40 type of fabric a needle is employed as shown in Figure 2 of the accompanying drawings embodying two latches 2 and 11 pivoted a suitable distance one below the other to the needle shank 3, and in the formation of a locked stitch the needle is projected to an extent sufficient to cause 45 new thread to be fed between the two latches, the old loop being cleared below the lower latch 11, and during the retracting movement of the needle 50 said old loop is passed over the two latches and a loop formed from the newly fed thread is knocked over while maintaining the old loop in the needle hook. During this retracting movement 55 of the needle the old thread loop is pulled down into the vertex 8 of the space between the top latch 2 and the needle shank; consequently if any scissoring action takes place between the said latch 2 and the opposed face of the shank, the said thread loop becomes nipped and is liable 60 to be cut or sheared. It will, therefore, be appreciated that by forming the upper latch 2 with the cranked portion 7 as before-described this danger of nipping and/or shearing is eliminated.

65 Additionally, in a needle constructed in accord-

ance with the present invention the pointed extremity 9 of the needle hook 1 and/or spoon or cup-shaped portion 10 at the tip of the latch 2 is/are so shaped that when the latch is completely closed upon the hook, the pointed extremity 9 of said hook is completely and snugly buried within said spoon or cup-shaped latch portion 10 thereby positively preventing the thread loop retained between the closed latch and needle shank from passing out over the hook between the pointed extremity of same and the coacting latch. 10

The last described characteristic is particularly advantageous when producing locked or tied stitches of the type before-mentioned as, in connection with such stitches, the thread loop to be 15 retained on the needle within the hook has, during the final knocking-over movement, a tendency to slide along the inner face of the latch and press itself out between the hook and latch tip. 20

I claim:

1. A knitting needle comprising the combination of a shank, a hook on said shank, a latch pivoted to said shank, a cranked part at the pivoted end of said latch, and the inner face of 25 said cranked part being shaped so as to provide for the angular space between shank and latch a vertex which is maintained at a substantially constant distance from the axis of the latch pivot throughout the final half of the closing movement 30 of the latch that is, from a position substantially at right angles to the shank of the needle to that wherein the latch is in engagement with the hook of the needle and lies approximately parallel with the stem of the needle below the hook. 35

2. A knitting needle having a combination of parts according to claim 1 and the latch having a pivoted termination which is eccentric to the latch pivot.

3. A knitting needle comprising a shank with a hooked extremity, a latch pivoted to said shank at a substantial distance from the hooked end thereof and free to swing into and out of engagement with the hook, the latch being of a length sufficient, when in engagement with the hook, to close a considerable space below the hook, and formed at its pivoted end of an involute shape whereby the said pivoted portion of the latch is cranked relative to the main stem portion thereof, and the adjacent facing edges of the needle stem and the latch adjacent to the pivot being such that the vertex of the space between these parts is maintained substantially constant during the movement of the latch from a mid-horizontal position to a vertical closing position, thus overcoming tendency for a thread lying in the said vertex to be sheared by the closing latch. 45

4. A two latch knitting needle adapted to be used in producing ladder-resisting fabrics, having its hooked end and the upper latch that co-acts therewith constructed as stated in claim 3, and its second latch located below said hook and latch. 50

ROBERT KIRKLAND MILLS. 65
